PACKAGE MAGAZINE

Filed Nov. 2, 1931

UNITED STATES PATENT OFFICE

EARL WESTON FARMER, OF MINNEAPOLIS, MINNESOTA, ASSIGNOR TO FAWCETT PUBLICATIONS, INC., OF MINNEAPOLIS, MINNESOTA

PACKAGE MAGAZINE

Application filed November 2, 1931. Serial No. 572,519.

My invention relates to package magazines. An object of the invention is to provide a magazine which comes to the purchaser in what looks like a box but which upon inspection will be found to be a magazine with sealed covers within which is contained the body of the magazine secured at its back to the covers while along with the magazine, there may be articles of manufacture or materials retained within the boxlike covers until the package is opened. A carrying medium is thus provided for such things as blueprints, photostats, patterns, special advertising matter, photographs, phonograph records, materials of construction for small or toy articles, etc. which may be supplementary and germane to the nature of the magazine. When the package is unsealed, any such enclosed material is immediately accessible, and upon tearing off sealing flaps with which the covers are provided, the purchaser has a magazine which is bound in covers in the nature of a book.

Another object of the invention is to provide novel means for binding or securing the covers and the pages of the magazine together, such means being of such character as to have a direct cooperation with the particular character of covers which are provided.

The full objects and advantages of my invention will appear in connection with the detailed description thereof, and the novel features of my inventive idea will be particularly pointed out in the claims.

In the accompanying drawing which illustrates a practical embodiment of my invention, Fig. 1 is a perspective view showing the package magazine in sealed condition. Fig. 2 is a plan view on a reduced scale showing the covers fully opened and with the magazine pages secured and an article to be enclosed in place. Fig. 3 is a perspective view showing one of the covers in open position prior to sealing. Fig. 4 is a plan view showing an adhesive applied to the flaps prior to sealing. Fig. 5 is a view of the package in transverse section. Fig. 6 is a perspective view of the magazine after the sealing flaps have been torn off.

As shown in the drawing, I provide a front cover member 10 and a rear cover member 12, these cover members being connected by a rear edge member 14, the width of which is preferably somewhat greater than the thickness of the pages 16 of the magazine for a purpose which will appear later. The cover members are preferably made of rather stiff material such as cardboard or boxboard. The front cover 10 and the rear cover 12 preferably join the rear edge member 14 in scored lines 18 and 20 respectively, whereby hinging movement of the covers 10 and 12 is provided. Two similar flap members 22 are carried by the top and bottom edges of the cover member 12, these flap members being provided with parallel scored lines 24 and 26 whereby top and bottom edge members 28 are provided which are substantially of the same width as the rear edge member 14. A flap member 30 is carried by the front edge of the cover member 12, this flap member being provided with parallel scored lines 32 and 34 whereby a front edge member 36 is provided of the same width as the rear edge member 14. It will be understood that the covers and attached flaps may be cut from the proper stock by means of dies or in any other suitable manner.

The pages 16 of the magazine may be of any desired number and material and are preferably produced by folding sheets of the material together along the middle thereof in well known manner. The pages, however, before being secured in the box covers are preferably secured together by a staple 38 set at the center of fold of the sheets. This may be done by placing the assembled sheets on a saddle along which the secured pages are adapted to slide. The staple 38 holds the pages together for trimming before they are placed in the box covers. The pages thus secured together and trimmed are then secured in the box covers by two staples 40 set through the two end portions of the cover structure and sheets whereby the latter are firmly secured within the covers. As shown in Fig. 5, the staples 40 are set through the upper scored line 18 and through the line of fold of the sheets. Due to this manner of

fastening and to the fact previously referred to that the covers are deeper in fold than the body portion of the magazine, space is provided in the bottom of the box in which any 5 desired small articles of manufacture such as previously mentioned may be placed. As shown, a phonograph record P has been placed in this space. It is to be noted that the phonograph record may be germane to 10 the nature of the magazine and that the inclusion thereof is not now allowable by the present method of manufacture of magazines. With the parts in the position shown in Fig. 3, an adhesive A is brushed across the 15 flaps 22 and 30 as shown in Fig. 4 and the cover 10 is pressed down so that the magazine assumes the form shown in Fig. 1 which it will be noted is drawn on a larger scale than the other figures. When the magazines 20 are stacked, the weight of superimposed magazines will hold the covers 10 in place until the adhesive has set sufficiently for this purpose.

The advantages of my construction of 25 package magazine over enclosing a complete magazine in a separate sealed box are obvious in view of the foregoing description. In my construction whatever attractive imprint is placed on the front cover is always visible 30 and no duplicate thereof is required in order that it may appear when on sale. The back cover may be utilized for carrying any matter which it is not only desirable to have exhibited in connection with the package but 35 which it is desirable to have permanently associated with the magazine. For instance, the back cover may carry an illustrated table of contents playing up the lead articles of the magazine in tabloid form. If features 40 of this sort were placed on a separate box, the cost of duplication would be involved as well as for the features of the front cover. Furthermore, when the seal is broken after 45 purchasing the magazine, the purchaser upon tearing off the flaps or tabs has a board-bound magazine with the addition of whatever materials or articles are enclosed with the magazine which material or articles cannot now with existing forms of magazine manufac- 50 ture be carried with the magazine. Thus it will be seen that a magazine having the characteristics above set forth is greatly broadened in the scope of magazine utility. My package magazine has important advantages 55 from a sanitary point of view. Any one purchasing the sealed magazine does so with assurance that it has not previously been thumbed over by another person of unknown identity and who may be of slovenly habits 60 addicted to the thumb moistening habit or affected with a contagious disease. The placing of the table of contents on the back cover is sufficient to apprise the prospective purchaser of what he may expect to find in the 65 magazine.

I claim:

1. A package magazine comprising a plurality of imprinted sheets forming the body of the magazine, cardboard covers to which the rear edges of said sheets are secured, said 70 covers being deeper in fold than said body portion whereby space is provided for enclosing articles of manufacture along with the body of the magazine, and flaps attached to said covers along scored lines, said flaps being adapted to be sealed to produce a complete 75 enclosure for the body of the magazine and said articles, and to be torn off on said scored lines to release said articles, and to leave a bound magazine.

2. A package magazine comprising a plurality of imprinted sheets folded together along the middle thereof and forming the body of the magazine, a staple securing said sheets together at the center only of the fold, covers for said sheets, a back edge member to which said covers are hingedly attached, staples passing through the end portions of said back edge member and through the end 80 portions of said fold, and flaps attached to said covers along scored lines, said flaps being adapted to be sealed to produce a complete 85 enclosure for the body of the magazine and to be torn off on said scored lines to leave a bound magazine.

3. A package magazine comprising a plurality of imprinted sheets folded together along the middle thereof and forming the body of the magazine, a staple securing said sheets together at the center only of the fold, covers for said sheets, a back edge member to which said covers are hingedly attached, staples passing through the end portions of said edge member at one of the hinges and through the end portions of said fold whereby 90 space is provided for enclosing articles of manufacture along with the body of the magazine, and flaps attached to said covers along scored lines, said flaps being adapted 95 to be sealed to produce a complete enclosure for the body of the magazine and said articles, and to be torn off on said scored lines to release said articles and to leave a bound magazine.

In testimony whereof I hereunto affix my 100 signature.

EARL WESTON FARMER.
